GLASS BREAKING HAND TOOL

Domenic Richard Corrado, Torrington, Conn.

Application April 19, 1946, Serial No. 663,439

5 Claims. (Cl. 81—3)

1

This invention relates to glazier's tools, and more particularly to a hand-operated glass-breaking tool adapted to remove a small block of glass from the edge of a previously cut section of plate glass.

One object of the present invention is to provide a glass breaking tool of the above nature in which the block is removed from the plate glass by a twisting action of said tool.

A further object is to provide a device of the above nature which will be especially useful in close quarters where only a small twisting movement of the tool is permitted, such as underneath an awning located above the plate glass installation of a store front or in the corner of a window.

A further object is to provide a device of the above nature which will be simple in construction, inexpensive to manufacture, easy to install and manipulate, compact, ornamental in appearance, and very efficient and durable in use.

With these and other objects in view, there has been illustrated on the accompanying drawing one form in which the invention may conveniently be embodied in practice.

In the drawings,

Fig. 1 is a vertical sectional view taken through a sheet of plate glass as it appears when being installed in a frame of a store window with the glass breaking tool in position to break away a small block from the edge of said glass in alignment with the usual window clip which is used to secure the edge of the glass to the face molding of the window frame.

Fig. 2 is a front view of the window frame and the plate of glass in which two rectangular blocks have already been broken from the left hand edge thereof.

Fig. 3 is a side view of the tool, shown by itself as it appears when in position for breaking away a block from the edge of the plate glass sheet and showing the method of twisting the tool to remove said block.

Fig. 4 is a top plan view of the same.

Fig. 5 is a side view of the same after the block of glass has been broken away.

Fig. 6 is a fragmentary perspective view of the edge of a sheet of plate glass showing a notch which has been broken in the edge thereof and the block which has been broken therefrom by the improved tool.

Referring now to the drawing in which like reference numerals denote corresponding parts throughout the several views, the numeral 10 indicates an elongated handle of the tool, which is circular in cross section and has a socket 11 at

2

one end for receiving a small connecting screw pin 12. The numeral 13 indicates generally a triangular metallic tool shank having a tapped socket 14 at its upper end for receiving the threaded end 15 of the connecting pin 12 so that the handle may be easily removable from the tool shank whenever desired.

In order to permit the tool to be operated in close quarters, the outer end of the tool shank 13 is provided with an inclined outer flat face 16 and a short inner flat face 17 parallel to the face 16. The shank also has a curved end 18 offset from the axis of the handle of the tool and the shank thereof. The curved end 18 is provided with a reversely turned tapered prong 19 having a flat outer face located in the same plane as the face 17. A rectangular slot 20 is provided between said prong 19 and the shank 13 of the tool—the angle of said slot being preferably about 28° to the axis of the shank of the tool handle.

As clearly shown in Figs. 1 and 2, a plate glass sheet 21 is first prepared by means of a glass cutter, not shown, with a plurality of short cutting lines 22 parallel to the edges of the top and sides of said sheet 21 from which blocks 23 of glass may thereafter be easily removed by means of the glass-breaking tool of the present invention. In Figs. 2 and 6, the notches left after the removal of the blocks are indicated by the numerals 24, and said notches are adapted to receive the usual clips for securing a glass-attaching face molding, not shown, located at the sides of the window frame 25.

The numeral 26 indicates an awning located at the top of the window frame.

Operation

In operation, when installing a sheet of plate glass 21 it will be placed alongside the window frame 25 below the awning 26 in the position shown in Fig. 1. The glazier will then cut or scratch the series of lines 22 along the edges of the plate glass sheet 21 at the positions indicated on Fig 2 of the drawing, these points being in alignment with the locations of the window clips, not shown, for securing the face molding of the window frame in position for securely attaching the plate glass sheet 21 in place.

The handle 10 of the improved tool will then be grasped and the rectangular slot 20 of the shank 13 will be placed over the edge of the plate glass 21 embracing one of the cutting lines 22. By twisting the handle in the direction of the arrows, as shown in Figs. 1 and 3, the glass block

23 will be easily broken away leaving a notch 24 in the edge of the glass 21. The screw which holds the face section of the metal may then be passed through the notches in the edge of the glass and will hold the plate glass securely in place.

One advantage of the present invention is that the glass breaking tool will not interfere with the awning 26 in any way and may be used in confined locations, store fronts, and other places very efficiently.

A further advantage is that the tool handle may be more easily grasped than with former types of glass breakers where the cutting parts were at right angles with the shank of the tool.

It will be understood that the tool of the present invention, if desired, may be made all in one piece and constructed of plastic, fiber, metal, or wood or other suitable material within the spirit and scope of the invention.

While there has been disclosed in this specification one form in which the invention may be embodied in practice, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a glass breaking tool, a handle, a tool shank having a curved end section laterally offset from the handle and shank, said curved end section having a rearwardly directed glass breaking slot therein, said slot being composed of plane surfaces in rectangular relation.

2. The invention as defined in claim 1, in which said slot is located at an angle of at least 20 degrees from the axis of the shank and handle of said tool.

3. The invention as defined in claim 1, in which the shank of said tool has a flat outer face which is inclined inwardly to said curved end section from a point adjacent said handle.

4. In a glass breaking tool, a handle, a forwardly convergent tapered tool shank, said tool shank having a curved end section laterally offset to one side of the handle and shank, and said offset end section having a glass breaking slot opening rearwardly at said side of the shank.

5. The invention as defined in claim 1, in which the end of said shank at one side of said slot forms a tapered prong offset from the body of the shank.

DOMENIC RICHARD CORRADO.
